[57] CLAIM

The ornamental design for a connector bracket for a collapsible tent frame, as shown.

DESCRIPTION

FIG. 1 is an overall side perspective view of the new and ornamental connector bracket according to the invention;

FIG. 2 is a back view of the connector bracket shown in FIG. 1;

FIG. 3 is a front view of the connector bracket;

FIG. 4 is a side view of the connector bracket taken from either side of the bracket;

FIG. 5 is a top plan view of the connector bracket; and FIG. 6 is a bottom plan view of the connector bracket taken from a position looking upwardly toward the bracket as shown in FIG. 1.

FIG. 4

FIG. 5

FIG. 6
